UNITED STATES PATENT OFFICE

2,602,457

MULTIPURPOSE HAIR-WAVING
INSTRUMENT

Michael E. Mele, Albany, N.Y.

Application January 26, 1950, Serial No. 140,680

2 Claims. (Cl. 132—19)

1

The present invention relates to a multipurpose instrument which is adapted for use in the home but is especially intended for use by hair-dressers and beauticians in beauty parlors and the like when giving permanent waves, tinting, or dyeing a customer's hair.

A single hand-manipulatable instrumentality with combined facilities for curling, combing and brushing hair is not new. In fact, it is old in the art to integrate such facilities into a single device or instrument. Reference is made for example to a patent to one Dorothy Hertzberg 2,272,151, February 3, 1942, which shows a brush characterized by a so-called rat-tail handle, a bristle supporting member formed integral therewith and of substantially circular cross section adapted to support a plurality of bristles, and an intermediate upright finger-engaging member radially disposed with respect to the handle.

The purpose of the present invention is to improve upon Hertzberg and other known patents and multipurpose hair-treating devices known to me. It is therefore an object, in addition, to provide a simple and practical multipurpose instrument in which manufacturers, users and others will find their expected needs fully met, contained and conveniently available.

More specifically, novelty is predicated on an integral body of commercial plastic or other suitable materials which is susceptible of being kept conveniently in a sanitary state and which is characterized by a rat-tail handle with an especially constructed head at one end, said head characterized by a comb, an obliquely offset adapter flange and tufts of brush bristles on said adapter flange, there being finger-gripping lugs at the juncture of the comb and handle so that the entire unit may be conveniently and securely grasped and turned axially to comb and brush the hair in an almost continuous rotary motion, which, as is known to those skilled in this technique, is so essential for effective tinting, hair dyeing and other hair arranging and setting operations.

Other objects and advantages will become more readily apparent from the following description and the accompanying illustrative drawings.

In the accompanying sheet of drawings, wherein like numerals are employed to designate like parts throughout the same:

Figure 1 is a perspective view of a multipurpose instrumentality constructed in accordance with the principles of the present invention;

Figure 2 is a side elevational view of the same observing it in a direction from right to left in Figure 1;

Figures 3 and 4 are cross sections taken on the planes of the lines 3—3 and 4—4 respectively of Figure 2, looking in the direction of the indicating arrows.

Referring now to the drawings by reference numerals and lead lines, the rat-tail handle, used for hair curling and wherever a mandrel is needed, is denoted by the numeral 6. The head on the outer larger end portion, the left-hand end in Figure 1, is characterized by a comb which is some two and half inches in length in practice, said comb denoted by the numeral 8 and including teeth 10 mounted as usual on a back 12. Formed integral with the back is an obliquely or laterally offset adapter flange 14 provided with a plurality of tufts of brush bristles 16. The flange 14 and two rows of bristles 16 collectively provide what is unitarily referred to as a brush 18. It will be noticed that the bristles at the left in Figure 1 do not extend out to the corresponding end portion of the comb. Instead, they terminate inwardly of said end. The bristles slant upwardly and are at an approximate forty-five degree angle to the teeth of the comb. In practice one might say that the brush 18 is about the size of a large-sized toothbrush or comparable in size with hair-tinting brushes now on the market. It is highly important that the brush bristles be spaced from the left-hand end of the comb so as not to interfere with the comb when it is used for parting and blocking one's hair.

The utility of the instrument is enhanced by having a pair of diametrically opposite lugs 20—20 provided at the juncture of the handle means 6 and multipurpose head means 8 and 18.

The device may be conveniently used when applying permanent wave solutions, hair rinses, hair tints, hair dyes, and in scalp treatments using lotions.

Due to the forty-five degree angular position of the brush in respect to the comb, the units 8 and 18 do not interfere with each other when the device is dipped into solution in a dish or a bowl and this is important as a time saver when applying hair tints and dyes.

It is quite possible by the separation and angularity of the brush and comb to apply different solutions on each and to still use them in unison or in proper sequences. By being able to simultaneously comb and brush the hair in one operation by properly twisting the wrist and

2

properly canting the comb in respect to the brush, much valuable time will be saved. Since time is of the essence in beauty parlors the combination facilities in a handily usable dual purpose instrument will be fully appreciated by beauticians, customers and others.

It is to be noted that the adapter flange 14 has its outer end definitely spaced some one-half inch or so from the outermost teeth and consequently the outermost end of the head or back 12. This is brought out in Figure 2. With the brush bristles thus located the front end of the comb does not interfere with the steps of blocking and parting a customer's hair while permanent waving same. The arrangement of bristles in the construction shown will not interfere with hair while combing during a tinting job and also will not cause dye to readily flow on an already dyed portion of the hair. Then, too, the adapter flange is at the correct angle to virtually eliminate, or to a great extent at least, dripping of solution onto the comb while either tinting or permanent waving.

The construction shown constitutes an excellent instrumentality for cold wave applicating purposes and assures thorough saturation and even distribution of the waving solution. With the angle at which the brush is set in relation to the comb the user is permitted to automatically brush the hair while completing the downward raking and thrust movement of the comb through the hair. Also this adaptation and arrangement of features when used in applying lotion eliminates loose hair from escaping from the curling rod.

The instrument is an ideal construction for blending vegetable rinses at home and makes for even distribution of the rinse and a uniform color through the entire head of hair by employing the dual purpose combing and brushing steps in practically one sweeping continuous motion.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice if desired.

Having described the invention, what is claimed as new is:

1. A multipurpose instrument for use in beauty parlors, the home and elsewhere comprising, in combination, a straight comb including a linearly straight back having right angularly disposed teeth, a rat-tail handle attached to, aligned with, and extending from the inward end of said back, a pair of opposed lugs formed on said handle at the juncture of said handle and said back, said lugs being diametrically opposite to one another and in a plane with one another and at right angles to said teeth, said back having an oblique-angled adapter flange projecting therefrom, and brush bristles mounted on and projecting outwardly at right angles from said flange, said bristles being situated within the marginal limits of said flange, the outermost bristles and the outer end of said flange being spaced inwardly from the corresponding endmost teeth of said comb to permit the comb and brush to function conjointly and simultaneously for combing and brushing and to prevent the bristles from interfering with the usual permanent waving steps of blocking and parting a customer's hair, and said lugs being spaced from the inward end of said flange.

2. The structure specified in claim 1, wherein said adapter flange is rectangular in outline and rectangular in cross-section and is disposed at approximately an angle of 45 degrees relative to said teeth and said lugs and being situated on a plane above the inward ends of said teeth.
